UNITED STATES PATENT OFFICE.

FREDERICK L. BOSTOCK, OF PITTSTON, PENNSYLVANIA.

TOOL.

1,109,507.

Specification of Letters Patent.

Patented Sept. 1, 1914.

Application filed August 26, 1912. Serial No. 717,148.

To all whom it may concern:

Be it known that I, FREDERICK L. BOSTOCK, a citizen of the United States, residing at Pittston, in the county of Luzerne and 5 State of Pennsylvania, have invented a new and useful Tool, of which the following is a specification.

The present invention relates to improvements in tools, the primary object of the invention being the provision of a handy tool 10 for use in hanging windows and doors, wherein the main body of the tool simulates a claw hammer and is provided, in the end opposite to the claw hammer, with a ratchet brace for reception of bits of varying characters.

With the foregoing and other objects in view which will appear as the description proceeds, the invention resides in the combination and arrangement of parts and in the details of construction hereinafter described and claimed, it being understood 20 that changes in the precise embodiment of the invention herein disclosed can be made 25 within the scope of what is claimed without departing from the spirit of the invention.

In the drawings—Figure 1 is a longitudinal sectional view through the complete tool. Fig. 2 is an end view of the brace end of 30 the tool. Fig. 3 is a section taken on line 3—3 of Fig. 1. Fig. 4 is a section taken on line 4—4 of Fig. 1.

Referring to the drawings, 1 designates a longitudinal member or shank, which as 35 shown is provided with a central bore or socket 2 for the removable reception of a saw blade 3, a spring clamp 4 being disposed at the mouth of the socket to retain the saw within the same, as clearly shown in Fig. 1.

40 A hammer head 5 is provided upon one end of the shank 1 and is formed with the claws 6 and striking head 7, the same providing in reality a cross head or handle for properly rotating, depressing or pulling longitudinally upon the shank 1, the purpose of which will presently appear. Formed below 45 the striking head 7 is a nail holder 8 having the longitudinally disposed outlet or throat 9, with the spring 10 disposed at the extreme 50 inner end of the holder and in a position to act as a cushion upon the head of the nail N and offering sufficient resistance to permit of the initial introduction of the nail into the surface, the nail being introduced to the 55 holder through the throat 9 and after the initial fastening to be removed therethrough.

The opposite end of the shank 1 is reduced and shouldered as at 11 for the reception of the metal cap 12 and disposed centrally of the shank and in longitudinal alinement with the socket 2 is a socket 13, said socket 13 being enlarged as at 14 for the reception respectively, of the spiral portion 15 and the supporting shank 16 of the brace 17. By means of the lug or pin 18, the brace may 60 be secured against rotation and sliding movement, this structure being conventional and similar to bit braces now in use.

As shown in Fig. 3, the pin or lug 18 is disposed for movement into and out of engagement with the member 16, the same being provided with the milled head 20 having the two notches a—a' for the reception one at a time of the spring pawl b, so that the pin 18 may be locked with its end seated 70 within the socket c to prevent the rotation of the brace 17 or be moved outwardly to 75 permit of the proper sliding and rotating movements thereof when operating a bit.

A plurality of sockets 21 are formed in the 80 incised end of the shank 1 about the bore 13 and provide a receptacle for the boring bit 22, the screw driver bit 23, and for the other tools that may be detachably connected to the brace 17. The spring clips 24 and 25 are provided for locking the bits 85 within the respective sockets so that the same may not be accidentally displaced during the manipulation of the tool.

The saw blade 3 is provided with a shank 90 to fit detachably in the brace 17, the brace 17, being locked against sliding and rotative movement when used in connection with the saw.

What is claimed is:

1. A tool comprising a hammer head, a handle carried thereby, a slot provided in said hammer head and lying upon the longitudinal axis of said handle and head, the said slot substantially U-shaped in cross section with the opening thereof extending at right angles to the plane defined by the longitudinal axis of the handle and head, during the nailing operation, said U-shaped slot disposed upon the rear of said hammer head, said U-shaped slot adapted to house a nail therein and adapted to hold the same. 100

2. A tool comprising a hammer head, a handle carried thereby, a slot formed in said hammer head positioned upon the longitudinal median plane of said handle and hammer head, the said slot disposed intermediate 105 110

the center of gravity of the said hammer head and said handle and approximating the center of percussion, said slot U-shape in transverse cross section and opening at right angles to the plane described by the longitudinal axis of the handle during the nailing operation, said U-shaped slot adapted to house and hold a nail therein.

In testimony that I claim the foregoing as my own, I have hereto affixed my signature 10 in the presence of two witnesses.

FREDERICK L. BOSTOCK.
